FUEL PUMP

Irvin E. Coffey, Normandy, Mo., assignor to Carter Carburetor Corporation, St. Louis, Mo., a corporation of Delaware

Application March 18, 1942, Serial No. 435,248

3 Claims. (Cl. 103—150)

This invention relates to reciprocating pumps and more particularly to the type of fuel pump having an outflow or discharge stroke resiliently actuated which renders the pump automatically operable in proportion to the demand for fuel.

The greater number of present day pumps used in automobile practice are mechanically driven from some rotating part of the motor and, therefore, operate at a speed proportional to that of the motor. It is true, however, that the speed of the motor is not necessarily proper for controlling the speed of the pump for often the speed is too great, pumping fuel at a rate which is not required and resulting in over-heating of the pumped fuel with consequent loss thereof by evaporation.

The use of a reciprocating pump having a spring actuated over-flow or discharge stroke results in automatically reducing the action of the pump when the amount of fuel delivered exceeds the requirements, since when the pressure built up in the discharge line exceeds the spring pressure the pump will no longer reciprocate. However, to gain full advantage from the use of this type of pump it is important that sufficient capacity be available for peak requirements and at the same time, pulsating flow be avoided. These results, however, cannot be satisfactorily obtained by merely increasing the size of the reciprocating unit to increase capacity.

A great many pumps in use at the present time use a resiliently actuated discharge stroke and a positively actuated intake stroke which delivers a sharp blow to the diaphragm and actuating arm and in time breaks the arm or ruptures the diaphragm.

It is, therefore, a primary object of the present invention to provide a pump having yielding intake and discharging strokes and having in addition a second pump controlled in its reciprocation to alternate with the first pump in intake and discharge strokes whereby a more nearly constant flow may be maintained at peak requirements while maintaining a practical rate of reciprocation of both pumps.

It is a further object to construct a pump having alternately operated diaphragms in separate pumping chambers, both being resiliently actuated by mechanical means dependent upon operation of the engine.

A further object is to provide a pump having a pair of pump chambers with their diaphragms positively connected so as to space them an unvarying distance apart, and spring means to resiliently discharge one pump chamber as the

other pump chamber is being resiliently charged.

It is a further object to provide a pump with dual pumping diaphragms having a lever mechanism actuated by the engine for transmitting power to the springs actuating the diaphragms during both the intake and discharge strokes.

It is a further object to construct a pump having dual pumping chambers, a single inlet chamber in communication with both pump chambers and an outlet chamber in communication with both chambers and a pressure relief valve between the inlet and outlet chambers.

A further object of the invention is to provide a pump in which the possibility of the actuating means delivering a sharp blow to the pump diaphragm is eliminated.

The above and other objects of the invention will appear more fully from the following detailed description of the invention and from the attached drawings, which form a part of this specification and illustrate a preferred embodiment of the invention, in which:

Fig. 1 is a diagrammatic side elevation of an engine, with the improved fuel pump in place thereon.

Fig. 2 is a sectional view of the pump taken substantially on line 2—2 of Fig. 1.

Fig. 3 is a plan view of the pump.

Fig. 4 is a sectional view of the inlet and outlet chambers taken substantially on line 4—4 in Fig. 3.

Figs. 5 and 6 are sectional views of pumps embodying two modified forms of the invention.

As shown in Fig. 1, the pump embodying my invention is designated by numeral 1, and is shown for convenience in explaining its operation as installed as a fuel pump in operative connection with an internal combustion engine of the type generally used in industry, motor vehicles, motor boats, air craft and the like and generally indicated by numeral 2. The pump is used to draw fuel from the fuel tank 3, through conduit 4 and force the fuel to the carburetor 5 through conduit 6.

To better understand the invention reference is directed to Figs. 2, 3 and 4. The hollow pump casting 10 is secured to engine 2 by bolts (not shown). The pump casting is provided with a vertical cylindrical chamber 11 terminating at the top and bottom in annular recesses 13 and 14, respectively, for receiving portions of the pump diaphragms during the intake strokes of the pump, and a horizontal chamber 12 for accommodating the pump mechanism.

The pump diaphragm assembly comprises a

pair of diaphragms 15 and 16 spaced an unvarying distance apart by a spacer rod 17 having slotted ends for receiving keepers 18 and 19, and a pair of compression springs 20 and 21 surrounding spacer rod 17 to exert an outward pressure sufficiently to seal the diaphragms 15 and 16 against leakage between the backing washers 22 and 23, respectively. Springs 20 and 21 are of sufficient strength to eliminate the possibility of the diaphragms 15 and 16 being moved inwardly on rod 17 by fluid pressure built up in the compression chambers, and at the same time having sufficient strength to transmit from the arm 36 the forces essential to effect discharge from the compression chambers under normal pressure. The outer portions of the diaphragms function as gaskets between pump housing 10 and the top and bottom castings 24 and 25, respectively, which are secured to the housing by screws 26. Top and bottom castings 24 and 25 are recessed to form pump or compression chambers 27 and 28 and include passageways 29 and 30, respectively, which, in turn, are in communication with the valved inlet and outlet chambers to be described later.

Solid pump lever 36 pivoted at 35 operating in the horizontal chamber 12, has one end 38a shaped to contact a revolving cam 37 of engine 2, while the other end 38 is forked and depressed at 39 to clear spacer rod 17 and to form seats for compression springs 20 and 21. Lug 40 depending from the pump arm 36 provides a seat for compression spring 41 of greater strength than spring 21 and functions to rotate the pump lever arm 36 clockwise thereby keeping the lever arm in constant contact with cam 37 while compressing spring 21 so as to discharge the pump chamber 28.

Passageways 29 and 30 are in communication with the inlet chamber 44 and outlet chamber 45 formed in the casting 10. Spring actuated valves, indicated at 46, 47, 48 and 49 are so positioned as to control the direction of fuel flow from inlet chamber 44 to outlet chamber 45 as diaphragms 15 and 16 are actuated to alternately charge and discharge the pump chambers 27 and 28.

An adjustable relief valve indicated at 33 is seated in a passageway 32 between the inlet chamber 44 and outlet chamber 45 by means of a spring compressed between the valve and a hollow plug 34 threadedly received in passageway 32 for varying the pressure applied to ball check 33 whereby the fluid pressure in outlet chamber 45 and compression chambers 27 and 28 may be limited.

It will be evident from the description that when cam 37 rocks the pump arm, pressure will be applied alternately to springs 20 and 21 which will, in turn, resiliently move diaphragms 15 and 16. The length of travel of arm 36 will be constant and dependent upon the throw of cam 37, while the travel of the diaphragms 15 and 16 will vary in accordance with the pressure built up in the compression chambers 27 and 28. Therefore, the pump will discharge in accordance with the demand for fuel, within limits, irrespective of the speed of actuating lever 36. It is also evident that if, perchance, pressure is built up in chambers 27 and 28 to a point equal to the pressure exerted by springs 20 and 21, the diaphragms will remain stationary until the pressure in the compression chambers is relieved. It will be further evident that springs 20 and 21 apply a gradually increasing pressure on the diaphragms to alternately charge and discharge the

compression chambers and the charging of one compression chamber starts when sufficient spring pressure is built up to move the diaphragm to discharge the other compression chamber. With this construction the possibility of transmitting a sharp blow from the lever arm to the pump diaphragms is eliminated and thus the life of the various operating parts will be materially increased.

When the engine 2 is started, cam 37 actuates pump lever 36 for applying pressure to spring 20 and as the pressure builds up, diaphragm 15 is moved outwardly to discharge the fuel from chamber 27 through passageway 29 and past check valve 47 into outlet chamber 45. During the discharge of fuel from chamber 27, diaphragm 16 has moved with diaphragm 15 causing fuel to be drawn from inlet chamber 44 past check valve 48 and through passageway 30 into compression chamber 28. When cam 37 has moved pump lever 36 to the length of its stroke, spring 41 then starts rotating pump lever 36 in the opposite direction thereby applying pressure to spring 21 causing diaphragms 15 and 16 to move in the opposite direction to discharge chamber 28 and charge chamber 27.

A modification of the invention is illustrated in Fig. 5 which is identical with Fig. 2 with the exception of the lever arm and compression spring 41 is eliminated. In Fig. 5 a pair of lever arms 50 and 51, pivoted at 35a have their outer ends 50a and 51a contacting opposite sides of the engine cam 37a and their inner ends 38a and 38b forming seats for compression springs 20a and 21a, respectively. By this construction, spring 41 in Fig. 2 is eliminated and springs 20a and 21a function to keep the rocker arms in constant contact with the engine cam 37a.

Another modification of the invention is illustrated in Fig. 6, showing a similar spring and lever arrangement as in Fig. 2 but acting upon a single diaphragm 15a which forms a movable wall for two compression chambers 27a and 28a. Compression chamber 28a, through which spacer rod 17a passes, is provided with a stuffing box comprising sealing rings 55, backing plates 56, compression spring 57 and plug 58, threaded into the body casting. Passageways 29a and 30a leading from the compression chambers 27a and 28a communicate with valved inlet and outlet chambers similar to those previously described in Figs. 2, 3 and 4.

The above is a full and clear disclosure of an illustrative embodiment of my invention by which the above results and advantages may be realized and various modifications of my invention may become apparent to those skilled in the art and the exclusive use of all modifications as come within the scope of the appended claims is anticipated.

I claim:

1. A pumping device for an internal combustion engine comprising a pair of pump chambers, a diaphragm wall for each chamber, a rod for spacing said diaphragms an unvarying distance apart, a pair of spring elements surrounding said rod for exerting an outward pressure against said diaphragms, a lever having one end arranged for contacting a cam of the engine and the other end interposed between said spring elements to transmit motion to one spring element for moving the diaphragms to discharge one pump chamber, and spring means acting to keep said lever in constant contact with the cam of the engine and transmit motion to the other

spring element for moving said diaphragms to discharge the other pump chamber.

2. A pumping device for an internal combustion engine comprising a pair of pump chambers, a diaphragm wall for each chamber, a rod for spacing said diaphragms an unvarying distance apart, a pair of spring elements encircling said rod for exerting an outward pressure against said diaphragms, and a lever having one end interposed between said spring elements and the other end arranged for contacting a cam of the engine for transmitting movement to said

spring elements alternately to charge and discharge said pump chambers.

3. A fuel pump comprising a pair of pump chambers, wall means for said chambers movable as a unit, an actuating stem projecting from said wall means, a pair of opposed, coiled, compression springs embracing and connected at opposite ends to said stem, and a reciprocating lever having an extremity gripped between said springs and also embracing said stem for applying pumping movements to said wall means.

IRVEN E. COFFEY.
